US0D1068542S

(12) United States Design Patent (10) Patent No.: US D1,068,542 S
(45) Date of Patent: * Apr. 1, 2025

(54) PENDANT

(71) Applicant: Dongguan Qinshi Jewelry Co., Ltd.,
Guangdong (CN)

(72) Inventor: Wei Tao, Hunan (CN)

(73) Assignee: Dongguan Qinshi Jewelry Co., Ltd.,
Guangdong (CN)

() Term: 15 Years

(21) Appl. No.: 29/980,086

(22) Filed: Dec. 23, 2024

(51) LOC (15) Cl. 11-01

(52) U.S. Cl.

USPC D11/79

(58) Field of Classification Search

(57) CLAIM

The ornamental design for a pendant as shown and described.

DESCRIPTION

FIG. 1 is a front, top, and left perspective view of a pendant showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom, and right perspective view thereof.

The broken lines shown in the drawings represent portions of the pendant that form no part of the claimed design.

1 Claim, 8 Drawing Sheets
